GUN MOUNT

Lee R. Frix, Knoxville, Tenn., assignor to Volunteer
Enterprises, Inc., a corporation of Tennessee

Filed Aug. 18, 1969, Ser. No. 18,753

Term of patent 14 years

Int. Cl. D22—02

U.S. Cl. D22—6

FIG. 1

FIG. 1 is a perspective view of the gun mount of the invention;

FIG. 2 is a side elevational view thereof;

FIG. 3 is an elevational view of the side opposite that shown in FIG. 2;

FIG. 4 is a left end elevational view of FIG. 1; and

FIG. 5 is a right end elevational view of FIG. 1.

The gun action is shown in broken lines in FIGS. 2 and 3 for illustrative purposes only.

I claim:

The ornamental design for a gun mount, as shown and described.
